UNITED STATES PATENT OFFICE.

CALVIN JACKSON, OF PHILADELPHIA, PENNSYLVANIA.

DESIGN FOR A SCREW-DRIVER HANDLE.

SPECIFICATION forming part of Design No. 32,013, dated December 19, 1899.

Application filed June 7, 1899. Serial No. 719,715. Term of patent 7 years.

To all whom it may concern:

Be it known that I, CALVIN JACKSON, a citizen of the United States of America, and a resident of the city and county of Philadelphia and State of Pennsylvania, have invented a certain new and original Design for a Screw-Driver Handle, of which the following is a specification.

My invention relates to a new design of screw-driver handle having the blade arranged at right angles to the handle.

Figure 1 is a plan view, Fig. 2 a top view, and Fig. 3 a cross-sectional view, of the handle proper of my new screw-driver handle.

15 My design consists, as shown in the accom-

panying drawings, of a handle *a*, terminating in a hollow cylindrical end *b*, arranged at right angles to the handle and extending laterally on each side beyond the plane of the handle, as indicated at *b' b''*. 20

What I claim is—

The design for a screw-driver handle substantially as shown and described.

Signed by me at Reading, Pennsylvania, this 31st day of May, 1899.

CALVIN JACKSON.
